UNITED STATES PATENT OFFICE.

MURRELL C. WARREN AND JULIUS J. KROHN, OF ARCATA, CALIFORNIA.

ATTACHMENT FOR BARREL-WINDLASSING MACHINES.

1,260,490.

Specification of Letters Patent. Patented Mar. 26, 1918.

Application filed August 7, 1917. Serial No. 184,843.

To all whom it may concern:

Be it known that we, MURRELL C. WARREN and JULIUS J. KROHN, citizens of the United States, residing at Arcata, in the county of Humboldt and State of California, have invented certain new and useful Improvements in Attachments for Barrel-Windlassing Machines, of which the following is a specification.

10 In windlassing a barrel, to position the truss hoop on the end thereof, it is at present the custom to loop a rope or cable around the barrel a short distance below the end thereof, and draw the rope or cable ends in 15 opposite directions, thus drawing the barrel stave ends together; by this method uneven pressures are applied to the staves and some staves are subjected to a side strain, due to the friction of the rope or cable over the 20 surface thereof, and an unsymmetrical barrel is the result.

Our present invention relates to an attachment designed for use in connection with windlassing machines for windlassing barrels, and by the employment of which, the windlassing rope or cable is guided, the speed of bending the staves is equalized and the edges thereof are brought in contact at the same time, thus insuring a symmetrical 25 barrel. The use of the attachment also eliminates undue compression and friction at the point of crossing of the windlassing rope or cable and gives a truly round circumference to the barrel overcoming the necessity of 30 leveling the barrel after windlassing and before trussing.

The invention consists primarily in providing a flexible spring member, bent to a radius slightly greater than that of the barrel to be windlassed and of a length to extend half way around the same, the spring member being provided with cable or rope guides for receiving the cable or rope passing around the barrel and longitudinally of 40 the spring, the tightening of the cable by drawing the opposite ends thereof in opposite directions drawing the edges of the barrel staves together at the same time.

With the above mentioned and other objects in view, the invention consists in the novel construction and combination of parts hereinafter described, illustrated in the accompanying drawings, and set forth in the claims hereto appended, it being understood 50 that various changes in the form, proportion, size and minor details of construction

within the scope of the claims may be resorted to without departing from the spirit or sacrificing any of the advantages of the invention.

To more fully comprehend the invention, reference is directed to the accompanying drawings, wherein:

Figure 1 is a view in plan of the preferred embodiment of our invention.

Fig. 2 is a view in side elevation, with a barrel positioned within the spring arms and illustrating the windlassing cable tightly encircling the same.

Fig. 3 is a view in plan, of the construction and arrangement illustrated in Fig. 2.

Fig. 4 is a central sectional view through the support.

Fig. 5 is an enlarged detailed plan view of the spring arms, support, and windlassing rope or cable guide.

In the drawings, wherein like characters of reference designate corresponding parts throughout the several views, 1, indicates a suitable support to which is attached in any 50 suitable manner, one end of a bracket 3, substantially T-shaped in plan. The outer surface of the bracket head 4, which is slightly curved, is provided with a longitudinal recess 5, in which is received the 55 central portion of the yieldable curved guide member 6, preferably of spring material. The guide member is removably secured within said recess of the supporting means, and the radius of the curve of said 60 guide is slightly greater than that of the barrel to be windlassed and said yieldable guide is of such length as to extend approximately half way around the windlassed 65 barrel.

The guide member 6, is preferably reduced in thickness from its center toward its opposite ends and the rear face of each end of said guide is provided with a suitable eye 9, through which pass the windlass 70 rope or cable 10, portions of which cross at A within the bracket 2 and pass through a transverse guide 11 therein.

By crossing the rope or cable 10, as at A, a loop B for encircling the barrel end, as 75 in Figs. 2 and 3 of the drawings is provided.

The opposite ends of the windlass rope or cable 10 are secured to any suitable form of pulling means commonly employed in barrel windlassing machines, and when tension is 80 applied to said opposite ends the portion of the loop B extending beyond the arm 6 is 85

drawn around the barrel simultaneously with the drawing together of the free ends of the guide member 6, from the position in Fig. 1 of the drawings to that in Figs. 2 and 3, thus placing an equal tension circumferentially of the barrel, and forcing the stave ends toward the center of the barrel until the side edges thereof are in meeting relation and insuring a barrel having a true end circumference.

It will be apparent that by making the guide 6 of such length as to extend approximately half way around the barrel to be windlassed and passing the windlass rope or cable over the exterior of the same, the frictional contact between the windlass rope or cable and the barrel staves adjacent to the crossing point A is overcome. The spring of the guide 6 expands the loop B around the barrel on the release of tension from the ends of the windlass rope or cable enabling the windlass barrel to be easily removed therefrom, and a barrel to be windlassed to be placed in its position.

Having thus described our invention, what we claim is:

1. An attachment for barrel windlassing machines, comprising a fixed support, a yieldable rope or cable guide member secured thereto, and curved to partly embrace a barrel, said guide provided with rope or cable guide openings through which the windlass loop forming cable or rope passes prior to crossing at a point within said fixed support.

2. An attachment for windlassing machines, comprising a fixed support, a yieldable windlass rope or cable guide member secured thereto, with its opposite ends projected beyond the said support and curved to partly embrace a barrel, the projecting ends of said guide formed on their rear faces with guide openings through which the windlass loop forming cable or rope ends pass prior to crossing at a point within said fixed support.

3. An attachment for windlassing machines comprising a fixed support formed with a transverse opening, a yieldable arm

fixed thereto and extending laterally from opposite sides thereof and lying in a substantially horizontal plane, said arms being curved to partly embrace a barrel and provided with guide openings through which the windlass loop forming or cable rope ends pass prior to crossing within said transverse opening in said fixed support.

4. An attachment for barrel windlassing machines, comprising a support, a spring arm extended from the opposite sides thereof in opposite directions to lie in a substantially horizontal plane and rigidly secured to said support, said arms bent or curved to embrace a barrel, and of a length to extend approximately half way around the same, a windlass rope guide carried on the rear surface of each arm adjacent its free end, and said support provided with an opening through which the crossing portions of the windlass loop forming rope or cable pass.

5. An attachment for barrel windlassing machines, comprising a fixed support, a member detachably secured to the face thereof and providing a flat spring arm extended from the opposite sides thereof in opposite directions to lie in a substantially horizontal plane, said arms tapering from their inner to their outer free ends and bent or curved to embrace a barrel, said arms being of a length to extend partly around a barrel, an eye carried on the rear surface of the free end of each arm and through which the loop forming portions of the windlass rope pass, said support provided in the rear of said spring arms with an opening through which the crossing portions of the windlass loop forming rope or cable pass, said eyes and opening arranged in alinement causing the rope to pass exteriorly of the spring arms and to lie in contact with the outer face thereof.

In testimony whereof we have signed our names to this specification in the presence of two subscribing witnesses.

M. C. WARREN.
JULIUS J. KROHN.
